UNITED STATES PATENT OFFICE.

JOHN C. LINCOLN, OF CLEVELAND, OHIO.

ELECTRODE-HOLDER.

1,217,468.

Specification of Letters Patent. Patented Feb. 27, 1917.

Application filed July 22, 1916. Serial No. 110,644.

To all whom it may concern:

Be it known that I, JOHN C. LINCOLN, a citizen of the United States of America, residing at Cleveland, in the county of Cuyahoga and State of Ohio, have invented certain new and useful Improvements in Electrode-Holders, of which the following is a specification.

My invention relates to improvements in electrode holders of the type especially adapted for electric welding. In devices of this character it is necessary frequently to renew the carbon electrode or pencil when carbon is employed as the arcing electrode; moreover, the carbon rod by reason of its resistance and subjection to the heat of the electric arc becomes intensely hot. As a result it is a common experience that the metallic parts of the carbon holder are partially destroyed by the intense heat and the electrical contact soon becomes very poor. It is necessary, of course, to employ a conductor for conveying the arcing current to the carbon electrode, hence, the ordinary means for effecting heat and electric insulation are not available.

Moreover, the gripping mechanism preferably should be operative rearwardly of a suitable protective shield for safeguarding the hand of the user, and the electrode itself preferably is positioned at a convenient distance from the hand, so that the radiation of heat will not be excessive.

My invention contemplates the provision of suitable conductive gripping jaws for the electrode, which preferably are of carbon and afford a sufficient body for the flow of the electric current to prevent excessive heating. Moreover, the lever controlling these gripping jaws is electrically insulated and its finger-piece is extended through a protective shield provided for the hand of the user.

The features of my improvement will be more readily understood by making reference to the accompanying drawings wherein Figure 1 is a longitudinal sectional view of my improved device; Fig. 2 is an enlarged fragmentary view of the socket for receiving the carbon jaws above mentioned; Figs. 3 and 4 are similar fragmentary views illustrating the mode of inserting and removing the particular spool-shaped and subdivided carbon jaws herein set forth; Fig. 5 is a plan view of the complete device, and Fig. 6 illustrates one of the carbon jaws. Throughout the several figures of the drawings I have

employed the same character of reference to indicate similar parts.

The tubular member *a* forms the frame or shank of the device, rearwardly of which is positioned a wooden or other insulating handle *b*, and at its opposite end there is provided a casting *c*, such as is shown in Fig. 2. This casting is formed with a transverse socket or opening one-half (*c'*) of which is of less radius than the other half (*c''*), as is shown in the plan view. The diameters of the semi-circles describing the respective socket portions are positioned at an angle of approximately forty-five degrees with the axis of the casting, the purpose of which is to afford a ready means for inserting and removing the carbon jaws.

These jaws (*d*, *e*) preferably are vertically subdivided and together approximate a spool-shape, centrally cored at *f* to accommodate the carbon electrode *g*. The flanges *d'* *e'* of said jaws are approximately of the same radius as the portion *c''* of the socket so that they will slip therein, while the semi-cylindrical body portions *d''* *e''* of said jaws are approximately equal to the radius of the socket portion *c'*.

Fig. 3 illustrates the manner in which one of these semi-spool-shaped members may be inserted in the socket and upon suitably turning and inserting the second member they are positioned as shown in Fig. 4, whereby their respective flanges serve to hold the jaws in position within the casting. A stout spring *h* is positioned interiorly of the tube *a* and handle *b* and reacts through rod *i* and its plunger *i'* firmly to grip the jaws and electrode within the casting. A trigger *j* extending through slots in the tube *a* and pivoted to the rod *i* has an insulating finger-piece *j'* which extends through an opening provided in the non-conductive shield *k* secured to the handle. Current is supplied to the implement through an insulated conductor *l* and its screw plug *l'* forms the stationary abutment for the spring *h*.

With an understanding of the structure just described, it is seen that the electrode is adapted to receive current throughout the engaging inner faces of the carbon jaws and the resistance of these jaws is so small that they will not become excessively heated by the flow of the maximum current.

In consequence, the metal parts of the implement are protected from deterioration.

Moreover, the white hot electrode, when in use, is forcibly gripped by the jaws through the action of the spring and plunger and excellent electric contact is insured within the implement itself, despite the fact that the carbon jaws become disintegrated after continuous use. These parts, and the electrode, of course, are susceptible of being readily replaced whenever it is desired, and, in consequence, the life of the implement is indefinitely extended, as compared with one which requires metallic parts for gripping and conducting current to the highly heated electrode.

15 The spring preferably is protectively positioned interiorly of the handle, where it is unaffected by the intense heat.

Having now described the preferred embodiment of my invention, I claim as new 20 and desire to secure by Letters Patent the following:—

1. In an electrode holder, the combination with a handle member, of a socket supported thereby, a renewable lining of conductive 25 material therein, an electrode or terminal and means for adjustably holding said electrode within the lined socket, substantially as set forth.

2. In an electrode holder, the combination with a handle member, of an electrode receptacle carried thereby, a conductive body within said receptacle and engaging the electrode, a suitable electrode, and means for gripping the electrode and removably holding it within said conductive body, substantially as set forth.

3. In an electrode holder, the combination with a metal socket, of a subdivided carbon facing for the interior of the socket, a carbon electrode positioned interiorly of the facing and gripping means acting upon the carbon members, adapted to hold them in electrical contact within the socket, substantially as set forth.

4. In an electrode holder, the combination with a tubular handle, of a socket-member carried by the handle and adapted to receive the electrode, a movable part adapted to grip the electrode within the socket, a spring 50 positioned interiorly of the handle and acting upon said part, and a trigger associated with the handle and adapted to relax the

tension of the spring against the movable part for releasing the electrode, substantially as set forth.

5. In an electrode holder, the combination with a tubular metal socket, the same having semi-cylindrical sections of different radius forming its tubular bore, of semi-spool-shaped carbon members loosely fitting within the bore, and spring-acting means for gripping the carbon members within the socket, and holding the electrode therebetween, substantially as set forth.

6. In an electrode holder, the combination with a metallic receptacle having a transverse bore, of semi-cylindrical carbon members loosely fitting within said bore; the same being centrally cored out to afford extended contact surfaces, a carbon electrode 70 therein, and means acting within the receptacle for gripping the carbon members tightly about the electrode, substantially as set forth.

7. In an electrode holder, the combination with a metallic holder, of renewable carbon contact-making jaws, a carbon electrode positioned therebetween, and retractile means for adjustably gripping the electrode between the jaws, substantially as set forth.

8. In an electrode holder, the combination with a tubular shank, of a gripping member adapted to removably hold the carbon or electrode, a handle positioned at a distance therefrom, a shield beyond the handle, centrally slotted, and a finger-piece extending through the slotted shield and connected to actuate the gripping member, substantially as set forth.

9. In an electrode holder, the combination with a tubular insulating handle, of a spring therein, gripping means for the electrode at a distance from the handle actuated by the spring, a shield associated with the handle, and a finger piece positioned rearwardly of the shield for controlling the gripping means, substantially as set forth.

In testimony whereof I do now affix my signature in the presence of two witnesses.

JOHN C. LINCOLN.
